PULL INDICATOR

Joseph W. Wunsch and Harry Wunsch,
Brooklyn, N. Y.

Application May 22, 1931, Serial No. 539,240

1 Claim. (Cl. 265—24)

Our invention relates to hoisting mechanism and particularly to means for indicating the pull on the hoist rope or cable. For many purposes it is desirable to know the pull upon a hoisting 5 cable while it is in use.

The main object of our invention, therefore, is to provide simple but reliable mechanism which will indicate to the operators at any time just what the pull on the cable is. Such a device is useful for controlling the safe operation 10 of the hoist and also for testing purposes so that it may be applied for continuous use or occasional use as the occasion may require.

The accompanying drawing illustrates an end 15 view of a hoisting drum embodying the improved indicating mechanism.

The winding drum 5 may be of any suitable character and driven in any suitable manner to wind and unwind the cable 6, the pull of which 20 is desired to know. This drum is mounted on a suitable supporting frame 7, which in turn is mounted on a platform 8 which is pivoted at 9 to a stationary support. The opposite end of the platform 8 is supported on a resilient bar 25 10 which in turn is supported by knife edges 11. The knife edge 11' is also preferably interposed between the platform and the resilient bar.

It will be seen that the pull on the cable 6 will tend to depress the supporting frame 7 and the platform 8, thus displacing a part of the bar 10 an amount which will be a function of 30 the pull. This displacement can be measured in a number of ways. For instance, we have shown a lever 12 pivoted at 13 and having its movable 35 end connected to a rod 14 and a conventional form of indicator 15. A pin or knife edge 16 carried by the hoist frame 7 engages the lever

12 so that as the hoist frame is depressed it will depress the movable end of the lever 12 in proportion to the amount of depression of the frame. By properly calibrating the indicator scale the 5 pull on the cable may be indicated in any desired system of measurement such as pounds, kilograms, etc.

In this connection it should be understood that we use the term indicator broadly to cover any suitable form of device which will enable the 10 operator to determine what the pull has been. It is immaterial whether this indication is a temporary one by means of a pointer or whether the action of the indicator is recorded on a chart or otherwise registered or recorded. 15

We also wish it understood that the spring is typical of any suitable type of resilient support or resistance to the movement of the movable member of the system.

Changes in detail may be resorted to without departing from the principle of the invention. 20

We claim:

A pull indicator comprising a supporting frame, a pivot support for one part of the frame 25 and a resilient support for another part of the frame, a driving shaft rotatably supported by said frame, a winding drum carried on said shaft, a pulling cable secured to said drum, a lever associated with said frame and actuated 30 by movement of the frame caused by a tangential component of the torque of said driving shaft, and means connected to said lever for indicating the pull on said cable. 35
